CLAIM

The ornamental design for a center console boat T-top structure, as shown and described.

DESCRIPTION

FIG. 1 is a perspective view from the left side showing the new design;

FIG. 2 is a perspective view from the right side showing the new design;

FIG. 3 is a perspective view from the interior of the T-top showing the new design;

FIG. 4 is an enlarged left side view showing the new design;

FIG. 5 is an enlarged right view showing the new design; and,

FIG. 6 is an enlarged front view showing the new design.

The broken lines represent portions of the design that form no part of the claim.
